ATTY'S

UNITED STATES PATENT OFFICE

ALVIN V. ROWE, OF GALESBURG, ILLINOIS, ASSIGNOR TO ROWE MANUFACTURING COMPANY, OF GALESBURG, ILLINOIS, A CORPORATION OF ILLINOIS

TRELLIS

Application filed April 29, 1929. Serial No. 358,794.

My invention relates generally to trellis constructions and particularly to ornamental trellis work of the fan type.

Fan types of trellis constructions necessitate the flexing or bowing of a plurality of ribs and means must be provided to maintain these ribs or members in proper spaced relation. It is one of the primary objects of my present invention to provide an improved means of simple and durable construction for maintaining these ribs or resilient members in spaced relation.

More specifically, my invention contemplates the provision of a trellis construction having a spreader or spacer which may be conveniently applied to the resilient members or ribs of the trellis and which is so designed as to positively preclude the possibility of weakening the ribs at the point where said spreader means is applied.

It is also an object of my present invention to provide a spreader device which will not necessitate the penetration, puncturing or disfigurement of said ribs and to this end I propose to frictionally engage the inner opposed surfaces of the ribs and thereby retain said spreader in position.

Still another object of my present invention is to provide improved trellis work of the fan or spread type which will present a compact bulk for shipment and which may be very easily and quickly assembled for use.

These and numerous other objects and advantages will be more apparent from the following detailed description when considered in connection with the accompanying drawings, wherein—

Figure 1 is a front elevational view of an ornamental fan trellis which is representative of one embodiment of my invention;

Figure 2 is an enlarged fragmentary perspective view of the lower portion of the trellis shown in Figure 1 to more clearly disclose the application of the spreader member; and

Figure 3 is a detailed perspective view of the spreader, the same being shown detached from the trellis ribs.

Referring now to the drawings more in detail wherein like numerals have been em-

ployed to designate similar parts throughout the various figures, it will be observed that my invention relates particularly to fan trellis constructions, and for the purpose of illustrating one embodiment of the invention I have shown a fan trellis which is indicated generally by the numeral 10. This trellis comprises a body or base section 12 and formed integral with this base section is a plurality of resilient ribs 14. In manufacturing the devices, these ribs are formed by merely slitting the portion of the wooden strip which forms a continuation of the base 12. After the material has been slit so as to present the plurality of adjacently positioned ribs 14, these ribs must be flexed or bowed outwardly from the center.

In order to maintain the spread or flexed position of the ribs 14 I provide a spreader member which is indicated generally by the numeral 16. This spreader member 16 may be formed of any suitable material such as sheet metal. A plurality of spaced apertures 18 are provided which are designed to receive the ribs 14. The spacing of the apertures 18 will be determined by the position which the spreader member is to occupy upon the ribs. In this particular instance I have disclosed the spreader in a position approximating the lower extremities of the ribs and hence the spacing is much less than it would be if the spreader were to be used at a point farther removed from the base of the ribs.

The sections 20 positioned between the apertures 18 frictionally engage the inner opposed surfaces of the ribs and the spreader is thereby secured against inadvertent displacement longitudinally of the ribs. In addition to the apertures 18 and the sections 20 extending therebetween, I provide the spreader with a pair of flanges 22. These flanges 22 provide an effective means for preventing displacement of the ribs transversely of the spreader.

In other words, the flanges provide a reinforcement on opposite sides of the ribs so as to maintain the outer or lateral surfaces of the ribs coplanar. Thus, by using a spreader of my improved construction, the trellis ribs may be uniformly spread or bowed and at the same time said ribs may be secured against

lateral displacement so as to prevent unsightly lateral distortion.

My improved spreader should be clearly distinguished from means which have heretofore been employed to maintain the ribs in spaced or spread relation. It has heretofore been the practice in some instances to spread the ribs of a fan trellis by securing a strip or slat to one side of the ribs by means of nails and the like. In view of the fact that the ribs are comparatively narrow, and that the grain in the wood frequently varies, the use of nails or other means for penetrating the rib material not only serves to weaken the material at that point but in many instances causes cracking and breaking of the ribs. Attention is directed to the fact that my improved construction eliminates the necessity of using any auxiliary securing devices and particularly such devices which have a tendency to weaken the rib structure. It is also to be noted that my spreader device rigidly supports the ribs at the front and rear thereof as distinguished from devices heretofore employed which have necessitated the use of auxiliary fastening means applied at only one side of the ribs. Obviously, in such arrangements there is a tendency for the unsupported side to become distorted, thereby causing the upper portion of the fan structure to be curved laterally so as to destroy the desired coplanar arrangement. Across the top of the ribs 14 I secure a suitable spacer bar 24 and intermediate this spacer bar 24 and the spacer 16 I provide as many spacer bars as may be desired.

From the foregoing it will be apparent that my invention contemplates the provision of an improved trellis construction in which the ribs are not weakened as the result of the application thereto of a spacer bar. My improved spreader may be very conveniently applied after the ribs have been formed in the board, by merely inserting the extremities of the ribs into their respective companion apertures 18. The frictional engagement between the edges of the sections 20 and the inner surfaces of the ribs 14 serves to positively retain the spreader in position and likewise the engagement of the flanges 22 with the outer surfaces of the ribs cooperates to retain the spreader in position and to secure the ribs against lateral displacement. Through the agency of the flanges 22, the ribs are provided with equal support on both sides and hence the possibility of any lateral displacement thereof is prevented. No portion of the wooden structure is penetrated or in any way disfigured so as to cause the same to become weakened and said spreader may be applied to the ribs either at the factory or by the dealer or user. In other words, by employing the teachings of my invention, a fan type trellis construction is provided which may be con-

veniently packed for shipment and very easily and quickly assembled for use. Obviously, more than one of the described spreaders may be used on each trellis and hence these spreaders may be made in various lengths to suit the particular needs incident to their use.

Having thus described my invention, what I claim as new and desire to secure by Letters Patent is:

A spreader for the base of a fan trellis, said device being formed from flat metallic stock and including a central web portion, said web portion being provided with a plurality of spaced non-circular apertures which completely traverse said web and are adapted to receive trellis members having a non-circular cross section corresponding in shape to said apertures, and side sections extending along the oppositely disposed margins of said web section, the lines determining the upper margins of said sides being substantially coincident with the outermost extremities of said apertures, whereby to enable substantially the entire inner surfaces of said side sections to frictionally bear against the adjacent surfaces of trellis members positioned therebetween and thereby secure said trellis members against lateral and rotative displacement.

In witness whereof, I have hereunto subscribed my name:
